US0D1091026S

(12) **United States Design Patent** (10) **Patent No.:** **US D1,091,026 S**
(45) **Date of Patent:** **** Aug. 26, 2025**

(54) **CHAIN CLEANER**

(71) Applicant: **Shenzhen Cylion Technology Co., Ltd,**
Shenzhen (CN)

(72) Inventor: **Bojie Xu**, Shenzhen (CN)

(73) Assignee: **Shenzhen Cylion Technology Co., Ltd,**
Shenzhen (CN)

(**) Term: **15 Years**

(21) Appl. No.: **29/923,517**

(22) Filed: **Dec. 29, 2023**

(30) **Foreign Application Priority Data**

Dec. 12, 2023 (CN) 202330815956.7

(51) **LOC (15) Cl.** **15-05**

CLAIM

The ornamental design for a chain cleaner, as shown and described.

DESCRIPTION

FIG. 1 is a front perspective view of a chain cleaner, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The broken lines in the drawings illustrate the portions of the chain cleaner, which form no part of the claimed design.

1 Claim, 8 Drawing Sheets
